UNITED STATES PATENT OFFICE.

WILLIAM D. MCCOY, OF ORANGE, NEW JERSEY.

SADDLE FOR VELOCIPEDES.

SPECIFICATION forming part of Letters Patent No. 476,479, dated June 7, 1892.

Application filed October 5, 1891. Serial No. 407,683. (No model.)

To all whom it may concern:

Be it known that I, WILLIAM D. MCCOY, a citizen of the United States, residing at Orange, in the county of Essex and State of New Jersey, have invented certain new and useful Improvements in Velocipede-Saddles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a saddle free from objectionable rigidity at all points on the seating-surface, while it will at the same time afford a firm and steady support for the rider.

A further object is to secure a tension in the flexible seat independent of the supporting-spring, whereby the elasticity of the said supporting-spring will not affect the said tension, to prevent the sliding of the rider on his seat when the vehicle receives a momentary check, to convert the saddle from a swinging seat to one that does not swing, and to secure other advantages and results, some of which will be more fully referred to in connection with the descriptions of the working parts.

The invention consists in the improved saddle and in the arrangements and combinations of parts, substantially as will be herein-after set forth, and finally be embodied in the clauses of the claim.

Referring to the accompanying drawings, in which like letters indicate corresponding parts in each of the several figures, Figure 1 is a side elevation of the improved saddle. Fig. 2 is a sectional view of the same, taken on line *a*. Fig. 3 is a detail side view of a certain sliding bearing for the spring upon which the flexible saddle is suspended, and Fig. 4 is a section of the same on line *y*. Fig. 5 is an inverted plan of the saddle. Fig. 6 is a rear elevation without the seat-support. Fig. 7 is an inverted plan showing a modification in construction, and Fig. 8 is a detail side view of a portion of the same.

In said drawings, *a* indicates a vertical bar connecting with the frame of the vehicle and which serves as the foundation or base of the spring-support, and *b* indicates a horizontal

portion, which in the ordinary vehicles has been integral with the vertical bar *a*, but in the present case is hinged or pivoted to said vertical bar, as at *c*. The horizontal portion *b* has thus a pivotal movement, and the vibrations—such, for example, as are caused by riding over ordinary paving-stones—are deadened before being transmitted to the main center spring.

The parts *a* and *b* are each provided with lateral projections *d* and *e* for a spring *f*, which last controls or governs the vertical play of the portion *b* and holds the same normally in a horizontal position.

The bearings *d* and *e* preferably consist of independent castings or pieces from the portions *a* and *b* of the Γ -rod, the said portions *a* and *b* being tubular sections and the said bearing-pieces being set in said tubes and held therein by brazing, rivets, bolts, or other mechanical means.

The spring *f* takes the weight of the rider, admits of limited vibration, and renders the riding more smooth and easy, as will be understood.

It will be noted that I have shown two methods of interposing the spring *f* between the bearings *d* *e*; but I am aware that other constructions varying from those shown may be employed without departing from this invention.

Upon the bar *b* is secured an adjustable seat *g*, held by a set-screw *h* or other suitable means, the upper surface of said seat being grooved or recessed to receive the main supporting-spring *i*, in which said spring is held by suitable clamps *j*. The main spring consists of a heavy wire or rod doubled at or near the cantle of the saddle, forming what we may term "lobes" or "divisions," which lie on opposite sides of the longer axial center of the saddle, as will be understood upon examination of Fig. 5. Each of said lobes is given the form of a loop of oblong shape, as shown in Fig. 1, which loop rests on the seat, as described. In forming the loops the wire rod, after having been bent to form the lobes, extends forward and downward, as at *k*, and is then turned backward to provide the bearing *l*, at which said spring rests upon the seat. The said portion *l* is laterally bent, as at *m*, to prevent any conflict or engagement with

part *k* when pressure is brought to bear. Each division of the wire is then bent, as at *n*, upward and forward to means for connecting the extremities with the distending-bar *t*.
 5 Said wire may here have a rigid relation to said distending-bar; but I prefer to allow a little play of parts.

The means preferred for connecting the extremities of the main spring to or with the distending-bar are shown more clearly in Figs. 1, 3, 4, and 5, and consist in a perforated block or piece *o*, through the center of which the distending-bar passes, and at opposite sides of said distending-bar the extremities 15 of the spring find bearings. As before indicated, I prefer to allow a little play of said extremities in said block, and to this end I form the perforations *p p*, as indicated in Fig. 4, so that when the portions *q* of the 20 spring change their angle under pressure there will be little, if any, binding of parts, such as will cause an interference with an easy sliding of the bearing-block on the distending-bar. A shoulder *r* in the spring 25 serves to limit motion in one direction and the extremities are upset, as at *s*, to prevent detachment. To secure the swinging effect, the bearing-block *o* slides on the distending-bar. To prevent such swinging, a set-screw 30 *d'* may be employed. At the front and rear of the flexible seat *e'* are secured the ordinary horn and cantle-plates *u* and *v*, the former of which is provided with a socket, and the latter is provided with bearings for a bracket *a'*, 35 which extends downward a short distance and at its lower extremity provides bearings for the distending-bar, said bracket being provided, preferably, with an angular perforation and set-screw.

40 The distending-bar *t* is preferably formed of a square rod, although it may have any other shape adapted to prevent turning. It is also preferably of steel brought to a spring temper, thus affording a yielding of the seat under the weight of the rider and relieves the 45 said seat of excessive rigidity of tension. By making the rod angular or other than round, or by using two rods, I am enabled to maintain a substantially horizontal action without 50 lateral or pivotal play, and thus insuring a positive longitudinal action of the part *o* and maintaining a correct relation of the pommel with the cantle.

When the set-screw *d'* in the bearing *o* is 55 not in contact with the rod *t*, the lobe-arms *q* are free to push the bearing forward along the rod *t* and to compress the spring *f'*. The sliding action of the bearing will take place whether the construction of the opposite arm 60 *k* and its connection with the cantle-plate be of the compound joint shown in Fig. 1 or of the simple hinge construction shown in Fig. 7; but to secure a backward-and-forward movement throughout the whole seat, as a distended body independent of the springs, I 65 have provided the double or compound hinge

connection consisting of a link *c'* and a swinging rear support *d''*, the said link joining the said spring at the union of the portions or arms *k* to the lower end of the said swinging support, and the said support extending upward from the said link to bearings provided between the bracket *a'* and cantle-plate. The said swinging support is bent to secure a limited though sufficient spring action therein. 75 To control the swinging of the seat, as described, and to cushion the vibrations, as will be understood, I have interposed the bearing-block *o*, to which the extremities *q* are secured between the springs *f' g'*, the said springs being adjustably held in place and in proper relation to the sliding bearing-block by collars *h' i'*. By these devices and operations the rider is relieved of the unpleasant sliding on the seat heretofore referred to 80 when encountering obstacles and inequalities in and of the roadway.

The distending-bar at its forward end is bent upward and forward to enter the socket of the horn or pommel-plate, and at its rear end it passes through the perforation in the bracket, where it is held by the set-screw *b'* to give the desired tension to the flexible saddle-seat. The forward end of the bar *t* is turned, as shown, or it may be spirally turned 90 to secure a limited but sufficient spring action. Thus the main supporting-spring at its opposite upturned extremities is connected with supplemental springs, which tend to further reduce unpleasant vibration and con- 95 due to the ease and comfort of the rider.

Having thus described the invention, what I claim as new is—

1. The combination, in a saddle, of a seat *e'* and means for tensioning the same, and a 105 spring *i* for supporting the same, said spring being connected at one end to said seat by a slide-bearing independent of said tensioning means and the other end of said spring having a hinged relation to said seat, substantially as set forth.

2. The combination, in a saddle, of a rigid or tensioned seat for the rider and a spring having forward and rearward projections, one of which is hinged to said seat and the other 115 having a sliding relation to said seat, free to slide without affecting the tension of the seat, substantially as set forth.

3. The combination, with a flexible saddle-seat and a distending-bar, of a spring providing a support for the seat, the said spring at one of its ends or pair of ends having a sliding relation to said bar, substantially as set forth and shown.

4. In combination, the flexible saddle-distending bar, supporting-spring *i*, and sliding bearing *o*, all said parts being arranged and adapted to operate substantially as set forth.

5. In combination with the bars *a b* and adjustable spring-seat *g*, a supporting-spring *i*, 130 having oppositely-extending arms or parts *k* and *q*, and a saddle-seat having an independ-

- ent distending-bar supporting said seat and supported at one end by said arms or parts *q*, substantially as and for the purposes set forth.
5. In combination with a saddle, a supporting-bar *a* and horizontal bar *b*, hinged thereto, and a spring *f* to cushion the vibrations, substantially as described.
7. In combination with a saddle, a support *a*, having a bearing *d*, a horizontal bar having a bearing *e*, and a spring *f*, interposed between said bearings and cushioning the vibrations of said horizontal bar, substantially as set forth.
15. 8. In combination with a saddle, a hinged support comprising the hollow or tubular bars *a b* and inserted bearing-pieces *d e* and spring *f*, arranged and combined substantially as set forth.
20. 9. In combination with the seat *g*, a spring *i*, bent in the form of a loop, with upwardly and oppositely projecting arms, supplemental springs attached to said arms and supporting the saddle-seat *e'*, and said seat, all arranged and combined substantially as and for the purposes set forth.
10. In combination with the seat *g*, a central main spring clamped thereon and having arms *k* and *q*, extending toward the cantle and pommel, respectively, and supplemental springs secured to said arms and supporting said cantle and pommel, substantially as set forth.
35. 11. The combination, with a seat *e'* and a distending-bar for giving tension to the same, of a supporting-spring having arms *k* and *q*, one of which is connected with the cantle and the other with the distending-bar, and said seat *e'* having said cantle, substantially as set forth.
40. 12. In combination with the supporting-spring with upturned arms or extremities, a saddle movable backward and forward independent of said spring, and springs for cushioning the backward and forward vibrations, substantially as set forth.
45. 13. In combination with the seat *g*, spring *i*, link *e'*, and swinging support *d''*, a seat *e'*, having cantle and pommel plates and bracket, a distending-bar *t*, and bearing-block *o*, all ar- ranged and adapted to operate substantially as and for the purposes set forth.
14. In combination with the seat *g*, spring *i*, link *c'*, and swinging support *d''*, a seat *e'*, having cantle and pommel plates and a depending bearing *a'*, a distending-bar *t*, secured in said bearing, and a sliding bearing *o*, arranged on said distending-bar and receiving the spring *i*, all said parts being arranged and adapted to operate substantially as and for the purposes set forth.
15. The combination, with the flexible saddle-seat and distending-bar, of a supporting-spring centrally located under the seat and having an independent relation to said bar in the matter of tension on the seat, so that when the tension is applied by means of the bar the said spring is in no way affected thereby, for the purpose set forth.
16. The combination, with a seat *e'* and a distending-bar for giving tension to the same, of a supporting-frame centrally arranged under the said seat and having arms *k* and *q* provided to admit of a downward movement, a slide *o*, adapted to admit of said movement of said arms, and a spring *f'*, limiting the movement of said arms, substantially as and for the purpose described.
17. The combination, with a flexible saddle-seat, of a tension-rod, and a bearing *o*, and a spring *i*, having a hinge connection with one of the terminals of the said seat and extending therefrom to the opposite extremity of the seat and engaging the bearing *o*, substantially as and for the purpose set forth.
18. The combination, with a flexible saddle-seat, of a tension-rod provided with a sliding bearing, and a spring *i*, having a hinge connection at one extremity of the seat and thence extending to the other extremity of said seat and engaging said slide-bearing, substantially as and for the purpose described.
- In testimony that I claim the foregoing I have hereunto set my hand this 3d day of October, 1891.
